UNITED STATES PATENT OFFICE.

THURSTON W. RICHARDSON, OF BEDFORD CITY, VIRGINIA.

TUCKER ATTACHMENT FOR SEWING-MACHINES.

1,082,360.

Specification of Letters Patent. Patented Dec. 23, 1913.

Application filed April 25, 1912. Serial No. 693,055.

To all whom it may concern:

Be it known that I, THURSTON W. RICHARDSON, a citizen of the United States, and a resident of Bedford City, in the county of 5 Bedford and State of Virginia, have invented certain new and useful Improvements in Tucker Attachments for Sewing-Machines, of which the following is a specification, reference being had to the accompanying drawings.

This invention relates to improvements in tucker attachments for sewing machines.

One object of the invention is to provide a tucker for sewing machines by means of 15 which cotton, linen, silk and woolen goods, leather or other material may be accurately tucked without creasing, marking or basting, and in which the tucks are turned above the material and are visible to the 20 operator.

Another object is to provide an attachment of this character which will be simple, strong, durable and inexpensive in construction, efficient and reliable in operation and well adapted to the purpose for which it is designed.

With these and other objects in view, the present invention consists in the combination and arrangement of parts as will be 30 hereinafter more fully described and finally pointed out in the appended claim, it being further understood that changes in the specific structure shown and described may be made within the scope of the claim without departing from the spirit of the invention.

In the accompanying drawings forming a part of this specification and in which like numerals of reference indicate similar 40 parts in the several views: Figure 1, is a perspective view of a portion of a sewing machine showing the invention applied thereto. Fig. 2, is a vertical longitudinal section of the same, Fig. 3, is a cross sectional view of the same taken on a line with the clamping screw of the adjustable space gaging bar of the tucker, and at right angles to the section shown in Fig. 2.

In the embodiment of the invention shown 50 in the accompanying drawings, 1, denotes a combined guide and gage plate, which may be of any suitable size and shape. In the plate adjacent to and parallel with one edge thereof is a slot 2, with which is engaged a thumb screw 3, whereby the plate is adjustably secured to the top plate of the

machine as clearly shown in Fig. 1, of the drawings.

On the end of the plate adjacent to the presser foot and needle of the machine is 60 an upwardly projecting guide flange 4, which extends parallel with the tucks and lines of stitching formed in the goods and serves as a guide for the goods while the tucks are being stitched and also as a gage 65 for forming tucks of different widths. In the flange 4, is a notch or recess 5, in the center of which is an upwardly extending tooth or fixed pawl 6, the purpose of which will be hereinafter described. On the plate 70 1, a suitable distance from the flange 4, and in line with the pawl 6, is a circular boss 7, having therein a threaded socket 8. Slidably engaged with the boss 7, and with the notch or recess 5, in the flange 4, is a combined guide and space gage 9, comprising a flat bar or narrow plate which corresponds in width to the width of the recess 5. On the end of the bar adjacent to the flange 4, is formed a downwardly and inwardly extending guide hook 10, which is adapted to be engaged with the folded edge of the last tuck formed while the next tuck is being stitched as clearly shown in Fig. 1, of the drawing.

In the gage bar 9, is formed a central longitudinally disposed slot 11, which extends substantially the entire length of the bar and has on one edge a plurality of teeth 12, which are adapted to be engaged with the tooth or pawl 6, said pawl thus firmly holding the bar in the position to which it has been adjusted. In order to hold the bar 9, down into engagement with the recess 5, in the flange 4, and the teeth 12, in engagement with the pawl 6, I provide a clamping screw 13, which is inserted through the slot 11, of the bar and is screwed into the threaded socket 8, of the boss 7. The screw 13, is provided with an enlarged head 14, which engages the upper side of the bar and clamps the latter into tight engagement with the boss. The screw 13, together with the recess 5, in the flange 4, with which the bar is engaged firmly holds the latter against 105 turning or lateral movement, while the engagement of the teeth 12, with the pawl 6, positively holds the bar against longitudinal movement and in the position to which it has been adjusted for spacing the tucks. 110 In order to readily determine the distance to which the bar has been adjusted and the

consequent spacing of the tucks, I provide the bar with a scale of measurement 15, which is preferably arranged on the upper side of the bar, as shown.

- 5 In applying and operating the device the plate 1, is placed on the top plate of the machine and adjusted on the screw 3, to space the guide flange 4, from the needle to a distance equal to the width of the tuck desired.
- 10 The first tuck is then formed by folding the material at the place desired and stitching the same in the manner indicated in the drawings. After the first tuck has thus been formed, the material is again folded back 15 with the tuck already formed, above or on the upper side of the goods. The guide hook 10, of the gage bar 9, is then engaged with the folded edge of the finished tuck and the clamping screw 13, of the bar is tightened 20 up and the bar thus held in the position to which it has been adjusted. This adjustment of the bar 9, will gage the distance between the rows of stitching and consequently 25 the space between the tucks as will be readily apparent by reference to Fig. 1, of the drawing. In forming the successive tucks the guide hook 10, of the gage bar is engaged with the preceding tuck as will be understood. It will thus be seen that no marking is required in making the tucks, therefore the tucks may be formed in silk or 30 woolen goods or other soft material that will not show a mark, without requiring the basting of the tucks. It will be also noted 35 that the tucks when formed are turned above and not below the goods as in the usual forms of tucks, and are thus at all times in plain view of the operator.

From the foregoing description taken in

connection with the accompanying drawings, the construction and operation of the invention will be readily understood without requiring a more extended explanation.

Various changes in the form, proportion and the minor details of construction may be 45 resorted to without departing from the principle or sacrificing any of the advantages of the invention as claimed.

Having thus described my invention, what I claim as new and desire to secure by 50 United States Letters Patent is:

A tucker attachment for sewing machines, comprising a combined guide and gage plate, means to adjustably attach the same to suitable part of the machine whereby the material is guided and the width of the tucks regulated, a guide flange on said plate, said flange having therein a recess, a fixed pawl in said recess, a tuck guiding and spacing bar slidably engaged with said recess and having therein a longitudinally disposed slot, a tuck engaging hook on one end of said bar, a series of teeth in said slot adapted to engage the fixed pawl on said guide flange whereby the bar is positively locked against longitudinal movement, a boss on said plate, having a threaded socket, and a clamping screw adapted to be inserted through the slot in said bar and screwed into the threaded socket of said boss whereby the bar is held down in operative engagement with the plate.

In testimony whereof I affix my signature, in presence of two witnesses.

THURSTON W. RICHARDSON.
